(57) **CLAIM**

The ornamental design for a versatile children's activity table with toy storage, as shown and described.

DESCRIPTION

FIG. 1 is a top, front and right side perspective view of a versatile children's activity table with toy storage showing my new design;

FIG. 2 is a top, front and left side perspective view thereof; FIG. 3 is a top, rear and left side perspective view thereof; FIG. 4 is another top, front and right side perspective view thereof;

FIG. 5 is a bottom, rear and left side perspective view thereof;

FIG. 6 is a front elevational view thereof;

FIG. 7 is a rear elevational view thereof;

FIG. 8 is a left side view thereof;

FIG. 9 is a right side view thereof;

FIG. 10 is a top plan view thereof;

FIG. 11 is a bottom plan view thereof; and,

FIG. 12 is an enlarged view of portion 12 in FIG. 1.

The broken lines in the drawings illustrate portions of the versatile children's activity table with toy storage which form no part of the claimed design.

The dash-dot-dash lines in FIGS. 1 and 12 are for the purpose of showing the area of enlargement and form no part of the claimed design.

1 Claim, 12 Drawing Sheets
